UNITED STATES PATENT OFFICE.

NATHANIEL G. FAIR, OF BRISTOL, TENNESSEE.

TINNER'S MACHINERY.

SPECIFICATION forming part of Letters Patent No. 271,440, dated January 30, 1883.

Application filed June 8, 1882. (No model.)

To all whom it may concern:

Be it known that I, NATHANIEL G. FAIR, a citizen of the United States, residing at Bristol, in the county of Sullivan and State of Tennessee, have invented certain new and useful Improvements in Tinner's Machinery, of which the following is a specification, reference being had therein to the accompanying drawings.

10 My invention relates to tinner's machinery; and it is designed for cutting tin, sheet-iron, and other thin metal. The several parts are so arranged that the material operated upon can be cut, whether it be angular, oval, convex, 15 or other form. The device is provided with a series of graduated scales, by the use of which I am enabled to dispense with patterns in shaping material to be cut.

The machine will do the combined work of 20 the square shears, stock-shears, circular shears, and dies. It operates in a smooth and rapid manner, and is easily adjusted for any of the purposes within its scope. It is operated by foot, steam, or other power. A balance or fly 25 wheel contributes its momentum, when set in motion, to the operative parts, so that a smooth action can be maintained by the operator. The foot-power is imparted through the medium 30 of a treadle, the treadle being connected to a lever which is provided with a pawl that works a ratchet-wheel. A light spring holds the pawl against the ratchet-wheel. The treadle and lever are forced down by the pressure of the foot and are thrown up by a spring. The 35 ratchet-wheel is rigidly attached to one end of the main shaft. On the other end of said shaft is the balance-wheel. The ratchet-wheel is also fixed to the grooved wheel that works 40 under the vertical cutting-wheel. The downward movement of the treadle starts the ratchet-wheel, the grooved wheel, and, through the main shaft, the balance-wheel. The pawl on the lever engages the teeth of the ratchet-wheel in going down and passes freely back 45 with the upward motion of the treadle. By this means the several parts are set in motion, all of which will be more fully hereinafter described, and pointed out in the claims.

In the accompanying drawings, Figure 1 is 50 a perspective view of my invention. Fig. 2 is a central longitudinal section. Fig. 3 is a side

elevation of the ratchet-wheel, pawl, pawl-spring, lever, and treadle. Fig. 4 is a side elevation of the bridge carrying edge-turning wheel and attachments. Fig. 5 is a front elevation of bridge, edge-wheel, and attachments. Fig. 6 is a front elevation of parallel bars, lever, spring, dies, &c. Fig. 7 represents a modification (side elevation) of Figs. 4 and 5. Fig. 8 is a perspective view of the dies, the upper one, F², being provided with a bar having jaws which are designed to hold work of a peculiar form. Fig. 9 is a transverse section through the line *xx* of Fig. 2.

In the accompanying drawings, the letter A 65 is the frame, which is made of cast-iron.

B is a balance-wheel, to which is attached the cog-wheel C. The wheels B and C are rigidly fixed to the main shaft C'.

D is a pinion which meshes into the cogs of 70 wheel C.

D² is a shaft rigidly fixed on one end to pinion D. The other end of said shaft rests in a slot, D⁶, in the bridge E.

D³ is a cutting-wheel which moves loosely 75 on the shaft D². Said cutter-wheel is provided with a sleeve, D⁴. Said wheel and sleeve are rigidly united and both move freely on the shaft.

D⁵ is a set-screw united with and passing 80 through the sleeve D⁴, and securing the same and cutting-wheel D³ to the shaft.

D' is a set-screw having a long shank, which passes down through the vertical face E' of the bridge E, and by means of which cutting-wheel D³ is pressed against the material to be cut.

F' is a lever, having a pivot, F⁵, by means of which it is attached to spring-bar H². To said spring-bar is rigidly attached a vertical 90 post, F⁶, and to the bottom of said post is the top die, F².

F⁴ is a small cross-piece attached to the end of lever F'. Said cross-piece is the fulcrum for the lever, and by means of which the top 95 die, F², is raised and lowered. The cross-piece F⁴ rests on the tops of and slides in grooves on the parallel bars F and F¹⁰.

F³ is the lower die, which is attached to the grooved bar H³.

H is a broad steel spring connecting bars H² and H³.

H' is a set-screw in spring H to increase or lessen the power of said spring.

F and F¹⁰ are two flat parallel bars, fixed at one end to the bridge F⁸ and at the other end to the bridge E at point D⁷. Bar F¹⁰ has a scale marked on its face.

F⁹ is a slot in bridge F⁸.

G is the face of the table, which has a longitudinal groove, G'.

H⁴ is a screw under the table to secure the adjustable bar H³, and by means of which said bar and dies, also upper bar, H², are held at any point in the line of the groove; or, in other words, a longitudinal adjustment of those parts is thereby effected.

K is a bar, the rear end of which is secured in a notch or depression in the top die-plate, F². On the outer end of this bar is formed an adjustable jaw or clamp, whose function is to hold oval and convexed material while being cut.

K' is the adjustable and K² the fixed under jaw. The straight back of the fixed jaw prevents the work from turning that may be placed against it. The dies turn on their respective posts, and thereby permit the bar K to turn while holding work to suit convenience.

K³ is the notch or depression in die F², into which the end of bar K fits.

I is the edge-turner attached to shaft I⁵. Said shaft has a crank or handle, I².

I' is a handle, pivoted at I³ to the shelf I⁶. A recess or collar, I⁴, is formed in the shaft I⁵. The shank of handle I' fits in said recess, and by a lateral motion of the handle the shaft I⁵ and edge-turner I are moved to and from the dies F² and F³. Said dies are made so that they revolve on their respective posts when holding material, and operated upon by the edge-turner. Said edge-turner is revolved, when desired, by the hand-crank I². The handle I' moves the turner to and from the material held by the dies.

I' is part of bridge F⁷. The recess therein is designed to aid in securing the same to the table. The other side of said bridge is secured by any temporary means to the table, so that the bridge can be removed at pleasure. The edge-turner and dies are designed for circular work. The dies secure the material, while the turner is revolved upon the edge of said material. By this means an edge on circular work can be easily and accurately turned.

J is a ratchet-wheel rigidly attached to the main shaft C'.

J³ is a pawl.

J⁴ is a light spring holding the pawl against the ratchet-teeth.

J' is a lever to which the pawl is attached. N is the treadle, the downward motion of which forces down the lever J', which action causes the pawl to engage the ratchet-teeth and forces the ratchet-wheel to revolve.

J⁵ is a metallic strap or band on the lever J'. Said band is cast or formed integral with the lever. The opening in the lever formed

by the band receives and encircles the ratchet-wheel. The pawl is also confined within the lever-opening.

J⁶ is a collar on shaft C'. The ratchet-wheel 70 is between said collar and lever J', the ratchet-wheel, grooved wheel, and collar being rigidly attached to shaft C'. The lever J' has a bearing on the shaft C' and moves loosely thereon, the shaft at one end being supported in slot C³ 75 of frame A. The treadle, lever, and pawl are thrown up by wire spring J². The spring acts as a counter-balance for the foot-pressure when the machine is operated by foot-power.

It will be seen that by starting the ratchet-wheel the grooved wheel M, the shaft C', cog-wheel C, and fly-wheel B are set in motion, inasmuch as they are intermediately connected. The cog-wheel C starts the pinion D, shaft D², and cutting-wheel D³. The wheels D³ and M 85 are thus respectively given a reverse motion. The wheel M has a series of beveled grooves on its face M', of different sizes.

When thin metal is to be cut the cutting-wheel D³ is placed in the smallest groove and 90 the metal placed between the wheels. The machine is then set in motion by the foot and the metal is severed. The edge of wheel D³ is beveled.

L is a gage for guiding work to be cut 95 square or straight. It has a thumb-screw, L', for securing it to the table. The graduated scale P on the table is to be used in connection with gage L.

R is a vertical finger or indicator attached 100 to the post F⁶. When circular work is to be cut it is secured between the dies F² and F³, and said dies and the bars securing them, H² and H³, are moved toward the cutter-wheel. The operator is enabled by the aid of finger R 105 and scale F' of the bar F¹⁰ to cut his material to any desired diameter. The dies are intended to hold material to be cut in a circular form, or hold round material, that the edge thereof may be turned by the beveled and adjustable wheel I.

Having thus described my invention, I claim as new and desire to secure by Letters Patent—

1. In a tinner's machine, the combination of the treadle N, lever J', strap J⁵, pawl J³, spring J⁴, collar J⁶, spring J², ratchet-wheel J, shaft C', and wheel M, as set forth.

2. The combination of the balance-wheel B, cog-wheel C, shaft C', pinion D, shaft D², cutting-wheel D³, sleeve D⁴, set-screw D⁵, and 115 beveled groove wheel M, as specified.

3. The combination of the beveled wheel D³, sleeve D⁴, shaft D², set-screw D⁵, wheel M, bridge E, and set-screw D', as set forth.

4. The combination of the wheels M and 125 D³, sleeve D⁴, shaft D², and set-screw D⁵, substantially as specified.

5. The cutting-wheel D³, sleeve D⁴, and set-screw D⁵, fixed to shaft D², and the adjusting set-screw D', in combination with the wheel 130 M, for the purposes set forth and described.

6. The combination of the grooved wheel

- M, ratchet-wheel J, pawl J³, spring J⁴, recessed lever J', and treadle N, for the purposes set forth.
7. The combination of the parallel bars F⁵ F¹⁰, bridges E F⁸, bars H² H³, and spring H, as set forth.
8. The combination of the bars H² H³, spring H, set-screw H', bars F F¹⁰, bridges F⁸ F⁷, handle F', post F⁶, and dies F² F³, as set forth.
9. The combination of the bars H² H³, spring H, set-screw H', dies F² F³, and lever F, as specified.
10. The combination of the bridge F⁷, handles I' I², and wheel I, substantially as set forth.
11. The combination of the bar K, provided with fixed jaw K² and movable jaw K', and dies F² F³, substantially as described, and for the purposes set forth.

In testimony whereof I affix my signature in presence of two witnesses.

NATHANIEL G. FAIR.
